NATURAL DRAFT OIL BURNER

John Ramsay Clark, Vancouver, British Columbia, Canada

Application October 28, 1946, Serial No. 706,126

1 Claim. (Cl. 158—91)

1

My invention relates to improvements in natural draft oil burners.

The object of the invention is to provide an oil burner of the so-called "pot" type in which substantially complete combustion is promoted with the resultant lack of smoke and lack of carbon coating of the flue surfaces, and to provide a construction where the base of the burner is kept relatively cool to prevent carbon deposit in the base of said pot.

Referring to the drawings:

Fig. 1 is a plan view, partly broken away, of the invention.

Fig. 2 is a sectional view taken on the line 2—2 of Figure 1.

Figure 3 is a sectional view of a cook stove fitted with the invention.

In the drawings like characters of reference indicate corresponding parts in each figure.

The numeral 1 indicates generally a cook stove having a fire box 2, an oven 3, a hot plate 4 and a flue 5 defined between said oven and hot plate. The fire box 2 is fitted with angle iron brackets 7 to support the pot burner 8 and a fire brick lining 9 for the upper part of the fire box, which will be referred to as the fire space 10.

The burner 8 consists of a generator body 12 having a bottom wall 13, side walls 14 and an inturned top wall flange 15. The generator body 12 is surmounted by a combustion chamber 17 having a peripheral wall 18 and is attached to a horizontal plate 19 at the periphery of an opening 20 formed therein. The generator body 12 is provided with a plurality of draft apertures 22 which are evenly spaced about its wall 14 for the admission of air to support combustion of the fuel. A fuel feed pipe 24 enters the wall 14 adjacent the bottom wall 13 and a shrouded opening 25 is formed in the side wall 14 adjacent the bottom to afford access to the generator for a taper to ignite the fuel therein.

Extending upwardly through the bottom wall 13 and substantially to the level of the top wall flange 15, is one or more open ended vertical tubes 27, each of which are restricted at the base as at 28 to impede the upward flow of air therethrough, so that the air will attain a high temperature before it discharges from the upper end of said tube.

The upper portion of the peripheral wall 18 is provided with rows of small staggered apertures 29 which are relatively small in diameter and two or more triangular zones 30 at the base of the wall are provided with larger apertures 31. The zones 30 are spaced from each other as shown.

2

The plate 19 is provided adjacent its long edge with a plurality of apertures 32 and is preferably provided with similar apertures 33 adjacent its short edges, all of which apertures communicate between the fire space 10 and the fire box or zone 2 below said plate 19, the opening 20 is substantially less than the diameter of the combustion chamber 17 and is surmounted by a disc 36 supported upon separators 37 and has a central aperture 38 through which the major part of the flame burns. The spacing of the disc 36 from the plate 19 permits secondary air admitted through the apertures 33 to combine with the flame and to preclude the possibility of the flame being blown out when a cover plate of the stove is raised, a failing which is common with many pot type burners.

As a means for preventing any tendency to smoking incidental to extensive change in the fuel being fed to the burner, I provide a plate 40 having supporting legs 41, which slips over the tubes 27 and stands upon the bottom wall 13 of the generator body 12, in spaced relation thereto. With the use of this plate, excessive heat is kept away from the central area of the oil in the generator, so that said oil will continue to burn solely in the annular space 43 between the plate 40 and the side wall 14.

In operation, fuel is allowed to flow into the generator body 12 and spread across its bottom wall 13 and then is ignited by means of an open flame inserted into the generator through the shrouded opening 25. The flame resulting, heats pipes 27 and causes an updraught therein, which draught is relatively slow owing to the restriction 28 at the base of the pipes, but by virtue of slow movement becomes heated to substantially the temperature of the generator flame. Air enters the generator body through the apertures in sufficient volume to support a flame from the burning fuel of relatively low heat, this incoming air serves to keep the flame spaced from the side wall 14 and prevents undue heat transfer to the bottom wall 13, thus preventing the carbonization of fuel upon said bottom wall. As the flame reaches the combustion chamber, it receives the highly heated air from the tubes 27 and relatively cool air from the small apertures 29 and from the larger apertures 31 of the triangular zones 30. The hot air from the tubes 27 assists in vaporizing any unignited fuel passing through the combustion chamber and the air from the apertures 29 and 31 intensifies said flame, air flow through the apertures 31 being less restricted than that flowing through the apertures 29 causes a high turbulence without causing noise in the

burner. The flame emanating from the top opening 20 of the combustion chamber spreads under the hot plate 4 of the cook stove and passes through to the flue 5 and in so doing is met with a small flow of highly heated air from the apertures 32 and 33 in the plate 19.

The device in operation, burns its fuel as effectively as a burner equipped with a blower and is quite noiseless and odorless due in a great measure to the high temperature of the air entering the combustion chamber and the turbulence set up therein and the cleanliness of the generator is largely due to the relatively low temperature of the base of said generator.

What I claim as my invention is:

An oil burner comprising a generator body having a bottom wall, apertured side walls and a top wall having an opening, a peripheral wall of lesser cross section than the generator body forming a combustion chamber and being carried upon the top wall of the generator body, said wall bordering the opening of the top wall of the generator body, said peripheral wall having a pair of zones of apertures separated circumferentially from each other and spaced diametrically opposite each other in said vertical wall and an air tube supported vertically in the bottom wall of the generator body, said air tube being open to the exterior of the generator body at its base and to the combustion chamber at its upper end, said

5 tube being restricted at its lower end and adapted to convey air from below the generator body and to deliver said air into the combustion chamber and at low velocity.
